UNITED STATES PATENT OFFICE.

JAMES H. EMACK, OF PHILADELPHIA, PENNSYLVANIA.

PROCESS AND MACHINE FOR VARIABLY CUTTING ROOFING SLATE.

Application filed October 9, 1922. Serial No. 593,341.

To all whom it may concern:

Be it known that I, JAMES H. EMACK, a citizen of the United States, residing at Philadelphia, county of Philadelphia, and State 5 of Pennsylvania, have invented a new and useful Improvement in Processes and Machines for Variably Cutting Roofing Slate, of which the following is a full, clear, and exact description, reference being had to the 10 accompanying drawings, which form a part of this specification.

The object of my invention is to so shape slabs or plates of roofing slate that when assembled together to form a roof, they will 15 give to the roof an appearance of antiquity. I accomplish this result by trimming those edges of the slabs that in the finished roof are exposed, in such manner that different slabs of slate will present edges of different 20 contour, the contours being so variable and irregular that the finished roof will present the appearance of having been so worn by long exposure. It is well known to impart to the edges of slate slabs contours different 25 from the more usual straightcut at right angles to the side edges, as, for example, to make such end edges of curved or pointed form, so that the finished roof will present a uniform pattern. My object, however, 30 is to avoid a pattern and to avoid uniformity and at the same time dispense with the necessity of providing a multiplicity of cutting tools of different shapes. I have attained my object by means of a single cutting 35 tool, by means of which I am able not only to obtain a number of different contours for the edges but am able theoretically to secure an infinite variety of contours and practically to obtain so many different contours that there is no perceptible precise 40 repetition of shape in the slates of an entire roof.

I accomplish my object by the provision of a tool having cooperating cutting edges 45 considerably longer, and preferably several times longer, than the edge of a slate, such cutting edges being of irregular broken form, usually notched or pointed at one or more points, and at most or all parts of 50 its length extending in a line that is curved or, if straight, is at an oblique angle to the side edges of the slate; whereby different pieces of slate may be subjected to the action of the tool at different locations along the 55 length thereof.

My invention may be best understood by reference to the accompanying drawings, in which—

Fig. 1 is a face or plan view of a portion of a roof composed of slates the exposed 60 edges of which are cut in accordance with my invention.

Fig. 2 is a front elevation of the machine.

Fig. 3 is a section on the line 3—3 of 65 Fig. 2.

Fig. 4 is a plan view of the upper blocks of the machine.

Fig. 5 is a vertical cross-section, on a large scale, through all the blocks of the 70 machine.

Upon the side members *a* of a stand is mounted a wooden block *b*. Above the block *b* is a second block *c*. The block *c* is recessed in its bottom face near its opposite 75 ends and in each recess is mounted a coil spring *d*, which normally holds the block *c* retracted above the block *b*. The coil springs *d* are guided on rods *e*, secured in block *b*. Rods *j* extend down from block *c* 80 through orifices in block *b* to a foot treadle *f* hinged to the rear member *g* of the stand.

Also supported upon the side members *a* of the stand is a third block *h*, which abuts sidewise against the block *b* and the upper 85 face of which is below the level of the upper face of block *b*. A fourth block *i*, abutting laterally against the block *c*, is recessed similarly to block *c* and is held a considerable distance above the block *h* (so 90 that its lower face is normally above the level of the lower face of block *c*) by means of coil springs *k*. The coil springs *k* are guided on rods *m*, which are secured rigidly with block *h* and extend loosely upward 95 through block *i* and upon which block *i* is slidable.

Dovetailed in the upper inner corner of block *b* is a clamping and shearing member *n*. Similarly inserted in the lower inner corner of block *c* is a clamping member *o*. Similarly inserted in the lower inner corner of block *i* is a shearing member *p*.

In plan view the cooperating edges of the members *n*, *o* and *p* extend in an irregular broken line *y*, as illustrated in Fig. 4. This line may be partly pointed, partly notched, partly straight and partly curved, as illustrated in Fig. 4. My invention, however, involves no particular form of irregular 110

edge, so long as the variation in departure from a straight line parallel to the direction of longitudinal extension of the blocks is sufficient to provide a multiplicity of overlapping sections having different contours. The length of these edges is necessarily considerably greater, and preferably several times greater, than the width of a slate, so that the slate may be inserted at any point 10 along its length.

In operating the machine, upon release of the foot treadle the block *c* is retracted from the block *b* by springs *d*, the slate is inserted lengthwise until its straight edge projects 15 a short distance beyond the members *n* and *o*, and the foot treadle is pressed down, compressing the springs *d* and holding the slate securely clamped.

By any suitable power means (not 20 shown), the block *i* is then depressed quickly independently of *c* so that the shearing member *p* strikes the projecting edge of the plate a sharp blow (all parts of the length of such projecting portion being struck 25 simultaneously), the shearing members *p* and *n* cooperating to sever the projecting cleanly without undercut; in other words, so that the edge of the slate, after severance, extends vertically at right angles to the upper and lower faces thereof. Upon release 30 of the power, the springs *k* lift the block *i* to its original position.

The operator will insert different slabs of slate at different positions along the machine. The possible number of such positions is substantially infinite, so that no two 35 finished slabs will present the same contour of trimmed edge; Figure 1 (containing a number of slabs of slate *x* assembled as in 40 roofing) giving an imperfect idea of the variety of contours which is obtainable by the use of my invention.

The invention is obviously not confined in its operation to slabs of slate, although 45 as applied to slabs of that material the in-

vention will probably find its most useful application.

Having now fully described my invention, what I claim and desire to protect by Letters Patent is:

1. The process of manufacturing slabs of slate with edges having an indefinite variety of contours which comprises subjecting the slabs to the action of a cutting tool having a cutting edge of substantially greater 55 length than the width of the individual slab and of such irregular broken contour that any substantial portion of its length is of different contour from any other substantial portion of its length, and presenting 60 the slabs to the cutting tool at a variety of lateral positions along the length thereof to produce slabs with trimmed edges having a variety of different contours.

2. The process of manufacturing slabs of slate which comprises positioning the slabs successively in different lateral positions with respect to a cutting edge of substantially greater length than the width of a slab and of irregular broken contour and 70 subjecting the slabs, so differently positioned, successively to a cutting action so as to produce slabs each having an irregular edge and with different slabs having irregular edges of a variety of configurations. 75

3. A slate trimming machine whose tool cutting edge is substantially longer than the slate edge to be trimmed, said cutting edge having an irregular broken contour so that any substantial portion of its length 80 is of different contour from any other substantial portion of its length whereby the contour of trimmed edges of different slate slabs may be varied substantially indefinitely with different lateral positionings of the 85 slabs relatively to said cutting edge.

In testimony of which invention, I have hereunto set my hand, at Philadelphia, Pa., on this 5th day of October, 1922.

JAMES H. EMACK.
